UNITED STATES PATENT OFFICE.

FRANK J. BAKER, OF DAYTON, OHIO.

SASH-MEASURING GAUGE OR THE LIKE.

Application filed March 23, 1927. Serial No. 177,522.

This invention relates to improvements in sash measuring gauge for windows.

In the accompanying drawings which serve for illustrating the invention:

Fig. 1 is a view of a window in vertical section illustrating the manner of applying the gauge;

Fig. 2 is a view of the sash stop;

Fig. 3 is a view in side elevation of the sash marker;

Fig. 4 is a plan view of the sash marker;

Fig. 5 is a view of the sash supporting member.

In the common practice in the building trades, wooden sash as furnished by the mills are oversize to allow for fitting the sash to the window opening, the over dimension allowed in the height of the sash being in the width of the lower sash rail of the lower sash. To fit the sash for height, both sash are hung in the window opening, the projection of the lower sash over the upper sash being measured at the meeting rails. The measurement is then transferred to the lower sash by applying a straight-edge and drawing a pencil mark along the lower edge of the sash to indicate the amount to be cut off for fitting the sash to the window opening. This method of marking the sash is not positive due to transferring the measurement from the meeting rail projection to the lower edge of the sash, it being common experience for inaccuracies to occur which result in misfitting of the sash. Also considerable time is required for making the measurement which adds to the cost of fitting the sash.

The sash measuring gauge as herein shown and described, is a simple and effective means for marking and fitting the sash accurately. With the use of the gauge the lower sash can be marked for cutting along its lower edge in a mere fraction of the time required in the common practice, and without possibility of inaccuracies occurring in the measurement.

The parts of the gauge, as best shown in the detail figures of the drawings, consist of a pair of friction grip brackets 1 adapted to be applied to the lower sash rail of the upper sash, as illustrated in Fig. 1, the brackets being provided with upwardly extended stops 2 for the lower sash as the same is raised for effecting the measurement and marking for cutting. To insure full contact of the upper sash with the head of

the window and for aligning one sash with the other, the lower sash is forced upward with moderate pressure into engagement with the stops of brackets 1 by wedge shaped members 3 which are pressed under the sash at its opposite lower corners, as illustrated in Fig. 1.

The sash marker is adapted to be moved freely over the window sill under the raised edge of the sash, as illustrated in Fig. 1. The marker consists of a handle 4 adapted to be disposed flat on the sill, the handle being turned upward at its outer end and provided with a stud 5 for supporting a toothed wheel 6, the height of the wheel above the under side of the handle being the same as the height of the lower surface of stops 2 above the lower edge of the lower sash rail of the upper sash. When the marker is moved over the sill from one side to the other of the window opening with the wheel 6 in pressure engagement with the outer face of the sash rail, a mark is inscribed along the lower edge of the sash which serves for locating the line for the saw cut for dressing the sash to size.

As the marker handle is kept in contact with the sill as the mark is inscribed on the sash, the mark will follow the surface line of the sill. Thus if the sill is not straight, the mark will vary from a straight line accordingly. By dressing the edge of the sash to the mark, the same will fit the sill as the window is closed.

The marker is also provided with a guide 7 the upper edge of which serves for supporting a pencil inscriber at the same height as the marker wheel 6 for marking the sash on the inside if desired. By cross marking the sash over the side edges between the opposite marks the angle of the saw cut for fitting the sash will be determined. In ordinary practice, however, only the outside marking of the sash will be necessary.

Having described my invention, I claim:

1. A sash measuring gauge for double-hung windows comprising a stop adapted to be applied to one of the sash, means for supporting the lower sash for effecting predetermined vertical spacing between the sash as determined by said stop, a sash marker supported at a height equal to the vertical spacing of the sash and operable over the sill from one side to the other of the window opening for inscribing a mark along the lower edge of the lower sash.

2. A sash measuring gauge for double-hung windows comprising a stop adapted to be applied by frictional engagement to the lower sash rail of the upper sash, means for supporting the lower sash against said stop for effecting spacing between the sash at the meeting rails, a sash marker supported at a height equal to the height of the stop above said lower sash rail and operable over the sill from one side to the other of the window opening for inscribing a mark along the lower edge of the lower sash.
3. A sash measuring gauge for double-hung windows comprising a stop adapted to be applied to the upper sash, a wedging member adapted to be pressed between the lower sash and the sill for supporting the sash against said stop and for effecting vertical spacing of the sash at the meeting rails, a sash marker supported at a height equal to said spacing of the sash and operable over the sill from one side to the other of the window opening for inscribing a mark along the lower edge of the sash.
4. A sash measuring gauge for double-hung windows comprising a stop adapted to be applied to the upper sash, means for supporting the lower sash against said stop and for effecting vertical spacing of the sash at the meeting rails, a sash marker supported at a height equal to said spacing of the sash and operable under the raised edge of the lower sash responsive to the surface variations of the sill from one side to the other of the window opening, and acting to inscribe a line conforming to the surface con-
- tour of the sill along the outside lower edge of the sash.
5. A sash measuring gauge for double-hung windows comprising a stop adapted to be applied to the upper sash, means for supporting the lower sash against said stop and for effecting vertical spacing between the sash at the meeting rails, a sash marker adapted to be operated under the raised edge of the lower sash over the sill from one side to the other of the window opening, including means for inscribing marks across the inner and outer faces of the sash at a height above the sill equal to said vertical spacing of the sash.
6. A sash measuring gauge for double-hung windows comprising a stop adapted to be applied to the upper sash, means for supporting the lower sash against said stop and for effecting vertical spacing between the sash at the meeting rails, a sash marker comprising a handle at one end and a toothed wheel at the opposite end supported at a height equal to said spacing of the sash, the marker being adapted to be operated under the raised edge of the lower sash with the marker wheel in engagement with the outer face of the sash and acting to inscribe a line along the lower edge thereof, and a guide supported intermediate the ends of the marker for inscribing a line across the inner face of the sash.

In testimony whereof I have affixed my signature.

FRANK J. BAKER.
